UNITED STATES PATENT OFFICE.

LOUIS M. ASPINWALL, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTROMAGNETIC SWITCH.

Application filed November 2, 1921. Serial No. 512,182.

My invention relates to switches and it has particular relation to switches for governing circuits traversed by moderately heavy currents.

5 One object of my invention is to provide an improved switch mounting whereby the switch may be readily installed and removed and be readily accessible to inspection.

10 Another object of my invention is to provide means for securing an initial pull between a pole-piece and an armature member of a switch that shall be much higher relative to the holding force, when the armature member is in contact with the pole piece, than is ordinarily obtained in switches of this character.

15 A third object of my invention is to provide an improved method of organizing the parts of a switch that will insure the contact members being in proper relation, the one to the other, when the switch is assembled.

20 Briefly speaking, my invention consists in employing a plurality of terminals of a switch to support it in a partially suspended position, in so organizing the pole-piece and the armature and its mounting that only a relatively small portion of each of the adjacent surfaces thereof may be brought into 25 contact and in securing the stationary contact member to the casting upon which the movable contact member is pivotally mounted, thereby avoiding the necessity of having precise distances, between centers of bolts, 30 that would otherwise be employed to mount the parts upon the base member of the switch.

25 For a better understanding of my invention, reference may be made to the accompanying drawings,

30 Figure 1 of which is a view, partly in side elevation and partly in section, of a switch mounted upon a car;

35 Figs. 2 to 4, inclusive, are views, in bottom plan and in side and end elevation, respectively, of the switch that is illustrated in Fig. 1 of the drawings;

40 Fig. 5 is a view, in perspective, of a casting constituting a part of the switch that is illustrated in Figs. 1 to 4 of the drawings; and

45 Figs. 6 and 7 are views, in side elevation and in plan, respectively, of the pole-piece

and armature member of the switch illustrated in Figs. 1 to 5, inclusive, of the drawings.

50 Referring particularly to Figs. 1 to 4 of the drawings, a switching device 1, which is provided with a base member 2 and two like circuit terminals 3 and 4, is mounted in a car 5, adjacent to the roof 6 thereof, partly by means of a plurality of stationary supporting members 7. The members 7 are spaced, the one from the other, by means of a block 8. The remaining supporting means 65 for the switching device constitutes the terminals 3 and 4, which are slidably mounted upon a plurality of rigid conducting members 9. The members 9 are mounted upon a stationary insulating member 11.

70 The terminals 3 and 4, which serve a two-fold purpose: first, to conduct electricity, and, second, to support the switch 1, are mounted upon the conducting members 9 by means of a plurality of nuts 12. The conducting members 9 are connected directly to a plurality of conductors 13, which constitute parts of the control system.

75 The supporting member 11 is mechanically connected to one of the frame members 14, constituting a part of the roof 6 of the car 5, by means of a plurality of metallic straps 15 and bolts 16. An insulating member 17, made preferably of asbestos board, is mounted in front of the terminals 80 3 and 4 of a plurality of switches 1, by means of an angle member 18 and a plurality of bolts 19.

85 A strip of insulating material 21 is secured to the base member 2, and, extending 90 parallel to the asbestos front member 17, serves to more rigidly maintain that member in position.

95 The stationary supporting members 7 and the block 8 are maintained in position by being secured to a clip angle member 23 by a plurality of bolts 24. The clip angle member 23 is secured to the side sheet 25, constituting a part of the car 1, by means of bolts or spot welding.

100 To inspect or remove the switch 1, it is necessary to remove only a cover member 26 and the asbestos board 17 to secure access to the bolts 12, which maintain the terminals 3 upon the stationary conducting members 9. After removing the nuts 12, the switch 1

may be pulled outwardly toward the center of the ear 5, thereby disengaging the base member 2 from the bifurcated support formed by the stationary members 7 and the block 8. A roof ventilator 26b is provided to permit air to circulate about the switches 1.

Referring now to Figs. 2 and 3 of the drawings, the main body of the switch comprises a magnetizable member 27 (see Fig. 5) that is provided with a plurality of projecting arms 28. These arms extend parallel to the base member 2 and serve to support an insulating cross piece 29, which is secured thereto by means of a plurality of tap bolts 31.

An arch shield 32 is provided for protecting the magnetizable member 27 from any arc that may be established between the contact members of the switch which are hereinafter described. A stationary control finger 33 is secured to the cross piece 29 by means of a relatively flat member 35 and a tap bolt 34.

The member 27 is also provided with a plurality of projecting arms 36 on which a lever arm 37 is pivotally supported by means of a pin 38.

The pivotally mounted arm 37 is provided with a plurality of projecting arms 39, on which a movable supporting and conducting member 40 is pivotally supported by a pin 41. A movable control finger 42 is secured to the supporting member 40 by a tap bolt 42a. The arm 37 is biased to its lower position by means of a spring 43. The movable control finger 42 is biased to the position illustrated in the drawing by means of a resilient member 44.

The control fingers 33 and 42 are provided with arc horns 45 and 46, respectively. A magnetic blow-out device, for extinguishing an arc that may be established between the control fingers 33 and 42 upon their assuming an open position, comprises a plurality of pole-pieces 47, which are mounted upon an arc box 48, a magnetizable pole member 49 and a coil 51.

The magnetizable member or casting 27 has a core member 52 mounted therein, which is surrounded by a magnetizing coil 53, having a plurality of terminals 53a. A stationary pole-piece 54 is mounted upon the core member 52 and may be engaged by an armature member 55, which constitutes a part of the lever arm 37.

For a better understanding of the movement of the armature member 55 in relation to the pole-piece 54, reference may be made to Figs. 6 and 7 of the drawings, which are views, in side elevation and in plan, respectively. The pole-piece 54 and the armature member 55 are triangular in shape and are of substantially the same size. When the pole-piece 54 and the armature

member 55 occupy the positions illustrated by the solid lines of Fig. 6 of the drawings, the adjacent surfaces thereof are situated directly opposite each other.

Upon the armature member 55 being articulated to its closed position, which is illustrated by broken lines in Figs. 6 and 7 of the drawings, the adjacent surfaces of the pole-piece 54 and the armature member 55 are in offset relation, the one to the other. In other words, much smaller active areas of the pole-piece 54 and the armature member 55 are employed to maintain the switch in its closed position than are employed for closing the switch. By this design of the pole-piece 54 and the armature member 55, the pull effected thereby to close the switch and the pull effected thereby to maintain the switch in its closed position are more nearly equalized. In other words, the initial pull exerted by the magnet has a greater value relative to the holding force for maintaining the switch closed than has been secured previously by switches of this character.

The operation of the switch 1 is effected by energizing the coil 53 by means of an auxiliary circuit comprising the terminals 53a. Upon the energization of the coil 53, a magnetic circuit, comprising the core member 52, magnetizable casting 27, lever arm 37, armature member 55 and stationary pole-piece 54, is energized to effect upward movement of the lever arm 37.

The lever arm 37 will move upwardly until the armature member 55 engages the stationary pole-piece 54. Prior to this engagement, the control finger 42 engages the stationary control finger 33, thereby establishing a circuit from the terminal 3 of the switch 1 through the magnetizing coil 51, metallic holding member 35, stationary control finger 33, movable finger 42, lever arm 37, shunt member 56, and conductor 57 to stationary contact terminal 4.

When the control fingers 33 and 42 are separated, the arc established therebetween is extinguished by the flux from the magnetic circuit, comprising the pole member 49 and the pole-pieces 47, which are energized by means of the blow-out coil 51.

From the above description, it is apparent that I have provided relatively simple means for mounting a switch by means of its contact terminals and a bifurcated supporting structure in which the base portion of the switch is slidably mounted. By having both of the control fingers secured to the casting 27, I have provided means for preventing the control fingers from occupying improper positions in their relation, the one to the other, because of incorrect distances between the centers of the supporting bolts when the control fingers are mounted separately on the base portion of the switch.

I have also provided means for insuring a relatively higher initial pull for closing a switch than is secured by apparatus constructed in accordance with the prior art.

While I have shown the switch in its preferred form, it is apparent that minor modifications may be made in the arrangement of parts without departing from the spirit of my invention. I desire, therefore, to be limited only by the scope of the appended claims.

I claim as my invention:—

1. In a switch, the combination with a plurality of magnetizable members of triangular shape, of means for so mounting said members that they occupy positions substantially opposite each other under one circuit condition and are in offset relation under another circuit condition.
2. In a switch, the combination with a plurality of triangular magnetizable members, of a pivotal support for one of said members that is offset from the plane of contact of said members.
3. In a switch, in combination, switching members operable to make and break electric circuits and magnetizable members for closing said switching members, said magnetizable members being disposed to effect a transverse relative movement during operation to vary the cross-sectional area of the magnetic path thereby to control the magnetic attraction between said members.
4. In a switch, in combination, switching members operable to make and break electric circuits, magnetizable members for closing said switching members, said magnetizable

members being disposed to effect a transverse relative movement during operation to vary the cross-sectional area of the magnetic path thereby to control the magnetic attraction between said members and means adapted to open the switching members when the magnetizable members are deenergized.

5. In a switch, in combination, switch members operable to make and break electric circuits, magnetizable members for actuating the switch members, contacting faces provided on the magnetizable members, said magnetizable members being disposed for operation to move the contacting faces transversely of one another to effect the setting of said contact faces in alinement when the switch members are open and in overlapping positions when the switch members are closed, thereby to control the magnetic attraction between said members.

6. In a switch, in combination, magnetizable members for actuating the switch, triangular contacting faces provided on the magnetizable members, said magnetizable members being disposed for operation to move the triangular faces transversely of one another to effect the setting of said contact faces in alinement when the switch members are open and in overlapping positions when the switch members are closed, thereby to reduce the magnetic attraction between said switch-actuating members as they move toward one another.

In testimony whereof, I have hereunto subscribed my name this 24th day of October, 1921.

LOUIS M. ASPINWALL.
